FOUNTAIN

Alfred W. Kaufmann, 1122 Ocean Ave., Brooklyn, N.Y.

Filed May 2, 1962, Ser. No. 69,932

Term of patent 14 years

(Cl. D91—4)

FIG. 1

FIG. 2

FIG. 1 is a perspective view taken from one side of a fountain showing my new design, the opposite side being essentially the same as the side shown and the bottom being substantially plain; and

FIG. 2 is a fragmentary cross sectional view thereof taken on line 2—2 of FIG. 1.

The side view of the fountain not shown is substantially the same in appearance as the side shown.

The bottom is plain and unornamented.

I claim:

The ornamental design for a fountain, as shown and described.
